WRAPPING MACHINES

Thord Ulrik Ullström, Bengtsfors, Sweden, and Fritz Wilhelm Fransson, Ottawa, Ontario, Canada

Application March 14, 1957, Serial No. 646,020

15 Claims. (Cl. 53—380)

This invention relates to wrapping machines for folding, against the ends of a cylindrical object which is to be wrapped, the edge portions of a paper web (or similar wrapper) placed around said cylindrical object and having greater width than the length of said object, of the kind provided with two parallel, rotatable rollers serving as a support for the object to be wrapped and arranged to impart to said object a rotating movement around its axis, and further being provided, at each end of the supporting rollers, with a fan-shaped pleating member which is secured to the free end of a rotatable shaft parallel to the supporting rollers and spaced from the axis of the object to be wrapped by a distance which is slightly greater than the radius of the object, the angular velocities of the object and the pleating member being timed in such a way, that during one revolution of the object, the pleating member performs several revolutions and thereby folds one part after another of the edge portion of the wrapper, so that these edge portions will form a series of overlapping folds.

The object of the invention is to provide a wrapping machine of the above-described kind which, irrespective of the greater or lesser stiffness of the wrapper material, will effect a smooth formation of folds which interlock, so that the folded edge portions of the wrapper will remain in a folded state.

The invention is mainly characterised by the fact, that a fan-shaped retaining member is arranged at the end of a shaft which is parallel to and rotating with the same angular velocity as the shaft carrying the pleating member, and which is situated between the last-mentioned shaft and the axis of rotation of the object to be wrapped, said retaining member being so adjusted in relation to the pleating member, that, during part of each revolution, it will hold the part of the edge portion of said paper web just folded by the pleating member against the part preceedingly folded by the pleating member.

In case the shafts of the pleating members and their respective retaining members are rotatably journaled in two bearing devices which are adjustable towards and away from each other, said bearing devices, according to the invention, may be supported by and displaceable along a guiding system which is disposed above and parallel to the supporting rollers and which is vertically displaceable in vertical guides disposed at the ends of the guiding system.

Other features of the invention will be apparent from the following description.

One embodiment of the invention is shown in the accompanying drawings. Figures 1 and 2 show the wrapping machine in two elevations at right angles to each other. Figure 3 shows, on a larger scale, the pleating and retaining members of one crimping unit in an initial position, and Figure 4 shows said members in one operative position. Figure 5 is a cross-section drawn to a larger scale along the line V—V in Figure 1 through the guiding system of the crimping units, and Figure 6 is a section taken on the line VI—VI in Figure 5. Figure 7

2

shows, partly in section and on a larger scale than Figure 1, one of the crimping units. Figure 8 is a section through the unit along the line VIII—VIII in Figure 7, and Figure 9 is a plane development of a guide groove for actuating the retaining member of the crimping units.

The main parts of the machine frame are constituted by two vertical guides spaced from each other and each comprising two uprights 3 and 4, at the upper and lower ends joined by means of cross pieces 1 and 2, and a horizontal top piece 5a connecting the two pairs of uprights. Vertically displaceable in each guide 3, 4 is a slide 5 and 6, respectively, which may be elevated or lowered by means of a screw 7 which is disposed between the uprights and journalled in the cross pieces 1, 2 and along which is adapted to run a nut (not shown) carried by the slide 5 or 6, respectively. Secured to the frame is an electric motor 8 which drives both screws 7 by means of a shaft 9 extending along the top piece 5a, the rotating government of said shaft being transmitted to the screws 7 by means of bevel gears 10. The slides 5 and 6 are interconnected by means of three horizontal guide rods 11, 12 and 13 which are parallel to each other and on which are displaceably carried two box-shaped bearing devices 14 and 15 for the crimping units which are more closely described hereinafter. Two feed screws 16 and 17 are arranged in axial alignment between and parallel to the guide rods 11—13. One end of each of said screws is journalled in a common bearing device 18 which is carried by the guide rods 11—13, halfway between the guides 3, 4. The other end of each of the screws 16 and 17 is journalled in one of the slides 5, 6. In the bearing devices 14, 15 of the crimping units nuts (not shown) are provided which run on said screws. The feed screws 16, 17 are driven by electric motors 19 supported by the slides 5 and 6, respectively, by means of a chain gearing 21 (Figure 2) housed in a casing 20. Below and along the feed screws 16, 17 there extends a key-grooved driving shaft 22 which at its middle is rotatably journalled in the bearing device 18 supported by the guide rods 11—13, and the ends of which are rotatably journalled in the slides 5, 6. An electric motor 23 carried by the slide 6 drives said shaft 22 by means of a chain gearing 24 (see Figure 2).

Each crimping unit comprises a pleating member in the form of a plate 24 and a retaining member 25, also in the form of a plate, each of said members being supported by the free end of its respective spindle 26 or 27, which is rotatably journalled in the respective bearing devices 14, 15, the spindles 26, 27 of one crimping unit being directed towards and axially aligned with the respective spindles of the second crimping unit. The pleating members 24 are directly secured to their spindles 26, while each of the retaining members 25 is secured to a sleeve 30 which is mounted on each spindle in such a way, that it is axially displaceable but not rotatable relative to the spindle. The bearing device 14 and 15, respectively, of each crimping unit has a sleeve 31 (see Figure 7) which is rotatably mounted on the driving shaft 22 and which is internally provided with projections engaging in the axial key grooves in the driving shaft 22. One end of the sleeve 31 is formed as a gear wheel 32 which, by means of an idling gear 33, drives a gear wheel 34 secured to the spindle 26 of the pleating member 24. By means of an idling gear 35, the gear wheel 34 drives a gear wheel 36 of same size secured to the spindle 26 of the retaining member 25. The sleeve 30 of the retaining member 25 is provided with a peripheral, endless guide groove 37, the shape of which is illustrated by the plane development shown in Figure 9. Engaging in said groove is a roll 40 which is rotatably journalled in a head 41 supported by an arm 42 projecting from the bearing device 14 or 15, respectively,

Simultaneously with its rotating movement, the retaining member 25, due to the co-action between the roll 40 and the guide groove 37, is given an axial reciprocating movement for each revolution of the spindle 27.

For the supporting of the cylinder-shaped object 44 (Figures 1 and 2) which is to be wrapped, two rotatable supporting rollers 45, 46, parallel to the guide rods 11-13, are arranged at the bottom of the machine. One of these rollers is driven in a suitable manner and thereby imparts to the object 44 a rotating movement around its axis. The fan-shaped pleating and retaining members in each crimping unit (see Figures 3 and 4) project in the same direction radially from their shafts and are situated in planes perpendicular to the geometrical axis of the object 44. When the machine is adjusted to the operative position, the crimping units are first lowered at each side of the object 44 so far, that the shaft 26 of the pleating member 24 will be situated slightly above the upper horizontal tangential plane of the object 44 and so that the shaft 27 of the retaining member 25 will be situated so far below the said tangential plane, that the retaining member 25 will be situated below said tangential plane also when in an upwardly turned position. After the crimping units have been adjusted vertically in this manner, they are moved, with the members 24, 25 in an upwardly turned position, towards the object 44 to a position, in which the pleating members 24 coincide with vertical planes situated close to the end surfaces of the object 44, whereafter the driving motor 23 of the pleating members is started.

From the initial position shown in Figure 3, the two members 24, 25 move at the same angular velocity in the direction implied by the arrows. During the first part of one revolution, the pleating member 24 in each crimping unit folds a part of the projecting edge portion 50 of the wrapper surrounding the object 44 towards the end surface of the object, while at the same time the retaining members 25, by action of the guide grooves, are moved in axial direction away from the object, thus keeping clear of the pleating member and the part of the wrapper's edge portion 50 which is being folded. After continued rotation of the members 24, 25, the pleating member 24 begins to turn away from the object, and the retaining member is rapidly moved towards the folded part of the wrapper's edge portion, so that the folded part is pressed by the retaining member against the end surface of the object. During the continued rotation of the object 44 and the members 24, 25, the pleating member 24 folds a part of the wrapper's edge portion adjacent the already folded part, whereafter the described cycle of operation is repeated until all of the edge portion has been folded against the end surface of the object. By adjusting the velocity of the driving supporting roller (45 or 46), the angular velocity of the object is adjusted in relation to the angular velocity of the pleating members in such a way, that each lap or fold formed by the pleating member will overlap and thereby lock the previously folded lap in its folded position. After a completed folding or crimping operation, the folded laps are secured by known methods, for instance by pasting sheets of paper or the like onto the end surfaces of the wrapped object. Without further explanation it will be obvious, that the machine may be used for wrapping objects of varying size, with respect to both length and diameter.

According to the invention, certain devices which will be described in greater detail below are provided for obtaining an automatic adjustment of the crimping units in accordance with the dimension of the object to be wrapped.

A sleeve 60 (see Figure 5) projects downwardly from the bearing device 18 and encloses an axially displaceable rod 62. To the lower end of the sleeve 60 is pivotally connected a foot 61 which is arranged to displace the rod 62 upwardly in the sleeve 60, when, at the lowering of the guiding device 11-13 carrying the crimping units, the foot 61 makes contact with the object to be wrapped.

The upper end of the rod 62 acts upon a switch 63 in the electric circuit of the motor 8, so that the current of the motor 8 and thereby the lowering of the crimping units is interrupted when the units are in the correct vertical position in relation to the object to be wrapped. During the lowering movement, the crimping units are spaced apart from each other. The feeler device described above is also arranged to close the circuits of the motors driving the feed screws 16, 17, simultaneously with the interruption of the lowering movement of the crimping units, whereby the crimping units are moved towards each other. This movement is automatically interrupted by the feeler mechanism shown at the bottom of Figure 7 and in Figure 8, when the respective crimping units have been moved to operative position with the pleating members situated in a vertical plane close to the end surfaces of the object to be wrapped and with the projecting edge portion 50 of the wrapper projecting in between the members 24, 25. The feeler mechanism in question consists of a rod 65 (Figures 7 and 8) displaceably carried in the sleeve-shaped shaft 27 of the retaining member. One end of the rod 65 is provided with a head 66 which normally projects slightly from the free end of the shaft 27 due to the action of a spring 67 acting upon the rod 65. When the head 66, at the movement of the crimping unit towards the object to be wrapped, makes contact with the end surface of said object, the rod 65 is displaced in the shaft 27 against the action of the spring 67, whereby the end of the rod 30 opposite the head 66, by means of a lever 68 (see Figure 8), causes a switch 69 to break the current to the motor 19 driving the feed screw 16 and 17, respectively, so that the crimping unit is stopped in the correct operative position. The shaft 27 of the retaining member 25 also encloses a compression spring 70, one end of which abuts against pins 72 secured to the sleeve 30 and projecting through longitudinal slots 71 in the side of the shaft. The axial movement of the sleeve 30 on the shaft 27 away from the object to be wrapped takes place against the action of said compression spring.

In connection with the stopping of the feed screws 16, 17 for displacing the crimping units towards the object to be wrapped, the feeler mechanisms last described are also arranged to start the driving motor 23 for the members 24, 25 which are thereby caused to operate in the manner previously described.

As is shown in Figure 5, the bearing device 18 also encloses a contactor 81 operated by a cam wheel 80 secured to the driving shaft 22. The contactor 81 is connected in the electric circuit of the driving motor 23 and combined with a limit switch arranged in such a way, that when the machine is stopped, the contactor is enabled to break the circuit only when the driving shaft 22 is in a certain position which corresponds to the position (initial position) of the members 24 and 25 shown in full lines in Figure 1 and in Figure 3.

The invention is not limited to the embodiment hereinbefore described and shown in the accompanying drawings, as the details of said embodiment may be modified in various ways within the scope of the invention.

What we claim is:

1. In a wrapping machine for crimping, over the ends of a cylindrical object which is to be wrapped, the projecting edge portions of a wrapper placed around said object, wherein is provided a pair of rotatable parallel rollers for supporting said object and imparting thereto a rotating movement around its axis, crimping elements disposed at each end of said supporting rollers and each comprising, in combination, a shaft positioned parallel to said supporting rollers, a fan-shaped pleating member secured to the free end of said shaft, a shaft parallel to the shaft carrying said pleating member, a fan-shaped retaining member supported by said second shaft for preventing the pleats of the wrapper's edge portion to unfold during the crimping operation, means for operating said

retaining member in timed relation to said pleating member, and means for rotating said shafts.

2. In a wrapping machine for crimping over the ends of a cylindrical object which is to be wrapped, the projecting edge portions of a wrapper placed around said object, wherein is provided a pair of rotatable parallel rollers for supporting said object and imparting thereto a rotating movement around its axis, crimping elements disposed at each end of said supporting rollers and each comprising, in combination a shaft positioned parallel to said supporting rollers, a fan-shaped pleating member secured to the free end of said shaft, a shaft parallel to the shaft carrying said pleating member, a fan-shaped retaining member, supported by said second shaft for preventing the pleats of the wrapper's edge portion to unfold during the crimping operation, means for operating said retaining member in timed relation to said pleating member, and means for rotating said shafts, two bearing devices having the shafts of said pleating members and the corresponding retaining members rotatably journaled therein, a guiding system disposed above and parallel to said supporting rollers adjustably supporting said bearing devices for movement away from and towards each other, vertical guides, and slides connected to said guiding system and vertically slidable on said guides for adjusting the vertical position of said guiding system.

3. In a machine according to claim 2, wherein a pair of rotatable feed screws are in threaded engagement with said slides and are connected to said guides, an electric motor operatively connected to said feed screws for rotating same, a source of electrical current connected to said motor, means for breaking the connection of said driving motor to said source of electrical current when said guiding system has been lowered to operative position relative to said object, a feeler mechanism carried by said guiding system and arranged to actuate said current breaking means when abutting against said object.

4. In a machine according to claim 2, wherein feed screws are rotatably supported along said guiding system and connected to said bearing devices for displacing the same, electric motor connected to said screws for rotating same, a source of electrical current connected to said motors, means for breaking the connection of said electrical current to said driving motors of said bearing devices when they have been moved to operative position relative to said object, feeler mechanism mounted on each of said bearing devices and arranged to actuate said current breaking means when abutting against the end surface of said object.

5. In a machine according to claim 2, wherein a pair of rotatable feed screws are disposed along said vertical guides and are in threaded engagement with said guiding system, an electric motor for driving said screw, a source of electrical current, an electric circuit connecting said motor to said source of current, a plurality of feed screws each situated along said guiding system and in threaded engagement with one of said bearing devices, a plurality of electric motors each for driving one of said bearing device feed screws, means for simultaneously breaking said electric circuit of the driving motor of said guiding system feed screws and closing the circuits of the driving motors of said bearing devices feed screws when said guiding system has been lowered to operative position relative to said object, said circuit-breaking and circuit-closing means comprising a feeler mechanism carried by said guiding system and a switch for being operated by said feeler mechanism when abutting against said object.

6. In a machine according to claim 2, in which a plurality of feed screws are each situated along said guiding system and connected to one of said bearing devices for displacing the same, electric motors for driving said screws, a source of electrical current connected to said motors, said guiding system comprising a number of horizontal rods, said slides supporting said rods and the

driving motors for said feed screws for displacing said bearing devices, one end of each of said screws being journaled in one of said slides and a common bearing supported by said guide rods having the other end of said screws journaled therein.

7. In a machine according to claim 2, in which each of said bearing devices is displaceable by means of a plurality of feed screws each situated along said guiding system and connected to one of said bearing devices for displacing same, a plurality of electric motors each connected to one of said screws for driving same, a source of electrical current connected to said motors, said guiding system comprising a number of horizontal rods, said slides supporting the ends of said rods and the driving motors for said feed screws for displacing said bearing devices, one end of each of said screws being journaled in one of said slides, a common bearing supported by said guide rods having the other end of said screws journaled therein, said means for rotating said crimping elements comprising an electric motor mounted on one of said slides and connected to said source of electrical current, a shaft driven by said motor extending parallel to said guide rods and being rotatably journaled in said slides, and a pair of gear wheels displaceably but not rotatably mounted on said shaft, transmission systems including said gear wheels arranged in said bearing devices for transmitting the rotating movement of said shaft to said crimping elements.

8. In a machine according to claim 2, in which a plurality of feed screws are each situated along said guiding system and connected to one of said bearing devices for displacing same, a plurality of electric motors for driving said screws, a source of electrical current connected to said motors, said guiding system comprising a number of horizontal rods, said slides supporting the ends of said rods and the driving motors for said feed screws for displacing said bearing devices, one end of each of said screws being journaled in one of said slides, a common bearing supported by said guide rods and having the other end of said screws journaled therein, said means for rotating said crimping elements comprising an electric motor mounted on one of said slides, an electrical circuit connecting said last mentioned motor to said source of electrical current, a shaft driven by said motor extending parallel to said guide rods and being rotatably journaled in said slides, and two gear wheels displaceably but not rotatably mounted on said shaft, a transmission system including said gear wheels arranged in said bearing devices for transmitting the rotating movement of said shaft to said crimping elements, a contactor carried by said bearing, a switch operable by said contactor connected in said electric circuit of said last-mentioned driving motor, a limit switch connected in said circuit, a cam secured to said driving shaft for operating said limit switch whereby said contactor is enabled to break said circuit only when said driving shaft and consequently also said crimping elements are in a given position.

9. A wrapping machine for crimping, over the ends of a cylindrical object, which is to be wrapped, the projecting edge portions of a wrapper placed around said object, comprising in combination, a pair of rotatable, parallel rollers for supporting said object and imparting thereto a rotating movement around its axis, crimping elements disposed at each end of said supporting rollers, and means for rotating said crimping elements, a pair of bearing devices supporting said crimping elements, a guiding system disposed above and parallel to said supporting rollers adjustably supporting said bearing devices for movement to and from each other and vertical guiding means supporting the ends of said guiding system for the vertical adjustment thereof.

10. In a machine according to claim 9, wherein a pair of rotatable feed screws are disposed along said vertical guiding means for supporting said guiding system, an

electric motor for rotating said screws, an electrical circuit for connecting said motor to a source of electrical current, means for breaking the electric circuit of said driving motor when said guiding system has been lowered to operative position relative to said object, said circuit-breaking means comprising a feeler mechanism carried on said guiding system and a switch in said circuit operable by said feeler mechanism when abutting against said object.

11. In a machine according to claim 9, wherein a plurality of rotatably mounted feed screws are situated along said guiding system and each connected to one of said bearing devices for displacing the same, a plurality of electric motors for rotating said screws, an electric circuit connecting said motors to a source of electrical current, means for breaking the electric circuit of said driving motors of said bearing devices when they have been moved to operative position relative to said object, said circuit-breaking means comprising a feeler mechanism mounted in each of said bearing devices and a switch in said circuit operable by said feeler mechanism when abutting against the end surface of said object.

12. In a machine according to claim 9, wherein a pair of rotatable feed screws are disposed along said vertical guiding means for supporting said guiding system, an electric motor for rotating said screws, an electrical circuit connecting said motor to a source of electrical current, a plurality of feed screws each situated along said guiding system and connected to one of said bearing devices for displacing the same, a plurality of electric motors for rotating the feed screws of said bearing devices, an electrical circuit connecting said motors of said bearing device feed screws to a source of electrical current, means for simultaneously breaking the electric circuit of the driving motor of said guiding system and closing the circuits of the driving motors of said bearing devices when said guiding system has been lowered to operative position relative to said object, said circuit-breaking and circuit-closing means comprising a feeler mechanism carried by said guiding system and a switch operable by said feeler mechanism when abutting against said object.

13. In a machine according to claim 9, in which a plurality of feed screws are situated along said guiding system and each connected to one of said bearing devices for displacing the same, a plurality of electric motors for rotating said feed screws, a source of electrical current connected to said motors, said guiding system comprising a number of horizontal rods, slides displaceable along said vertical guiding means supporting the ends of said guiding system and the driving motors for said feed screws for displacing said bearing devices, one end of each of said screws being journaled in one of said slides and a common bearing supported by said guide rods having the other end of said screws journaled therein.

14. In a machine according to claim 9, in which a plurality of feed screws are each situated along said guiding system and connected to said bearing devices for adjustably positioning same, a plurality of electric motors operatively connected to said screws, a source of electrical current connected to said motors, said guiding system comprising a number of horizontal rods, slides displaceable along said vertical guides and supporting the ends of said rods, said slides also supporting the driving motors for said feed screws for displacing said bearing devices, one end of each of said screws being journaled in one of said slides, a common bearing supported by said guide rods and having the other ends of said screws journaled therein, said means for rotating said crimping elements comprising an electric motor mounted on one of said slides, a shaft driven by said motor extending parallel to said guide rods and being rotatably journaled in said slides, and two gear wheels displaceably but not rotatably mounted on said shaft, transmission systems including said gear wheels arranged in said bearing devices for transmitting the rotating movement of said shaft to said crimping elements.

15. In a machine according to claim 9, in which a plurality of feed screws are situated along said guiding system and connected to said bearing devices for adjustably positioning same, a plurality of electric motors connected to said screws for rotating same, said guiding system comprising a number of horizontal rods, slides displaceable along said vertical guides and supporting said rods, said slides also supporting the driving motors for said feed screws for displacing said bearing devices, one end of each of said screws being journaled in one of said slides, a common bearing supported by said guide rods and having the other end of said screws journaled therein, said means for rotating said crimping elements comprising an electric motor mounted on one of said slides, an electrical circuit for connecting said last-mentioned motor to a source of electrical current, a shaft driven by said motor extending parallel to said guide rods and being rotatably journaled in said slides, and two gear wheels displaceably but not rotatably mounted on said shaft, transmission systems including said gear wheels being arranged in said bearing devices for transmitting the rotating movement of said shaft to said crimping elements, a contactor, a switch being connected in the electric circuit of said last-mentioned driving motor and operable by said contactor, a limit switch connected in said circuit, and a cam secured to said driving shaft for being rotated and operating said limit switch, so that said contactor is enabled to break said circuit only when said driving shaft and consequently also said crimping elements are in a certain position.
